United States Patent

Des. 235,577
Patented June 24, 1975

235,577

PAIR OF SPECTACLES

Larry G. Loughner, North Andover, Mass., assignor to
American Optical Corporation, Southbridge, Mass.

Filed Oct. 19, 1972, Ser. No. 298,894

Term of patent 14 years

Int. Cl. D16—06

U.S. Cl. D57—1 F

FIG. 1

FIG. 2

FIG. 3

FIG. 4

FIG. 1 is a front perspective view of a pair of spectacles embodying my new design;

FIG. 2 is a view from one side of the pair of spectacles, the opposite side being of substantially the same appearance;

FIG. 3 is a front elevational view thereof; and

FIG. 4 is a top plan view of the pair of spectacles.

I claim:

The ornamental design for a pair of spectacles, as shown and described.
